(57) **CLAIM**

The ornamental design for a display screen or portion thereof with a transitional graphical user interface component for identifying current location, as shown and described.

DESCRIPTION

FIG. 1 is a front view of a portion of a display screen or portion thereof with a transitional graphical user interface component for identifying current location showing a first image in a sequence according to a first embodiment of the design;

FIG. 2 is a front view of a second image in the sequence of the first embodiment of FIG. 1;

FIG. 3 is a front view of a portion of a display screen or portion thereof with a transitional graphical user interface component for identifying current location showing a first image in a sequence according to a second embodiment of the design;

FIG. 4 is a front view of a second image in the sequence of the second embodiment of FIG. 3;

FIG. 5 is a front view of a portion of a display screen or portion thereof with a transitional graphical user interface component for identifying current location showing a first image in a sequence according to a third embodiment of the design; and,

FIG. 6 is a front view of a second image in the sequence of the third embodiment of FIG. 5.

The process or period in which one image transitions to another forms no part of the claimed design. The appearance of the image transitions sequentially between FIGS. 1 to 2, FIGS. 2 to 1, FIGS. 3 to 4, FIGS. 4 to 3, FIGS. 5 to 6, and FIGS. 6 to 5.

The broken lines illustrate the display screen or portion thereof and form no part of the claimed design. The broken lines illustrate portions of the graphical user interface and form no part of the claimed design.
